UNITED STATES PATENT OFFICE.

ELI E. SAGER, OF LOS ANGELES, CALIFORNIA.

CARBONATOR.

Application filed January 16, 1922. Serial No. 529,767.

To all whom it may concern:

Be it known that I, ELI E. SAGER, a citizen of the United States, residing at Los Angeles, in the county of Los Angeles and State of California, have invented a certain new and useful Carbonator, of which the following is a specification.

My invention relates to a large capacity carbonator, and the objects of my invention are: first, to provide a carbonator of this class which will mix and deliver large quantities of the carbonated liquid in a reasonable length of time; second, to provide a carbonator of this class in which the liquid is thoroughly and highly carbonated; third, to provide a carbonator of this class which is free from any moving parts; fourth, to provide a carbonator of this class which cools and keeps cool the carbonated liquid; fifth, to provide a very efficient carbonator; sixth, to provide a novelly constructed carbonator; seventh, to provide novel control mechanism for carbonators, and eighth, to provide a carbonator of this class which is simple and economical of construction, durable, easy to adjust and operate, and which will not readily deteriorate or get out of order.

With these and other objects in view as will appear hereinafter, my invention consists of certain novel features of construction, combination and arrangement of parts and portions as will be hereinafter described in detail and particularly set forth in the appended claim, reference being had to the accompanying drawings and to the characters of reference thereon which form a part of this application, in which:

Figure 1 is a sectional view through the center of my carbonator and showing some of the parts in elevation to facilitate the illustration; Fig. 2 is a sectional view of the feed valve through 2-2 of Fig. 1 showing the operation of said valve and showing fragmentarily by dotted lines a shifted position of the handle; Fig. 3 is a sectional view through 3-3 of Fig. 1 and showing a portion of the cover 2 broken away to facilitate the illustrations; Fig. 4 is a sectional view through 4-4 of Fig. 1 showing a portion of the bottom broken away fragmentarily, and Fig. 5 is a fragmentary sectional view through 5-5 of Fig. 4.

Like characters of reference refer to similar parts and portions throughout the several views of the drawings.

The tank member 1, upper head 2, lower head 3, bolts 4, discharge nozzles 5 and 6, overflow conductor 7, supply conductor 8, check valve 9, conductor 10, valve 11, supply pipe 12, fittings 13, 14, and 15, discharge conductor 16, gauge 17, mixing chamber 18, perforated discs 19, conductor 20, coil 21, distributing chamber 22, strap 23, valves 24, outer tank 25, base 26, casing 27, insulating material 28 and cover 29 constitute the principal parts and portions of my structure.

The tank member 1 is made of suitable material and it is provided with heads 2 and 3 at its upper and lower ends respectively and secured to said tank member by the bolts 4. The lower head 3 is provided with three orifices 3^a, 3^b and 3^c adapted to receive the nozzles 5 and 6 and the overflow conductor 7 respectively. Said nozzle 5 is adapted to discharge water or any other desired liquid into said tank and is connected to the supply main 8. Positioned in said supply line is a check valve 9 to permit the liquid to flow only in the direction indicated by the arrow shown in Fig. 4 of the drawings. The tube or nozzle 6 is closed at its upper or free end and is provided with a plurality of holes 6^a. Said nozzle is adapted to discharge and mix carbonic acid gas, or similar gases for charging liquids with the liquid in said tank, and is connected with the conductor 10 which is in turn connected with the carbonic acid gas supply line 12 through the two-way double action valve 11, for which I have filed a separate application for Letters Patent, Serial Number 529,560, dated January 16, 1922. The carbonic acid gas under pressure is delivered from the usual cylinder (not shown), or other source, to the supply line 12. The exhaust and overflow conductor 7 is also connected to the valve 11 through the fittings 13, 14 and 15. The liquid or gas passing through the conductor 7 is discharged through the conductor 16 by means of the valve 11. When the handle 11^a of said valve is in the position shown by solid lines in Fig. 2 of the drawings the valve member 11^b is disengaged from its seat 11^c thus permitting the gas or liquid to flow from the conductor 7 to the discharge or overflow conductor 16. When the handle of said valve is in the position shown by dotted lines the valve member 11^b engages its seat 11^c while the valve

2
 member 11^a is disengaged from its seat 11^c, thus permitting the gas from conductor 12 to pass to the conductor 10 and therefore to the perforated discharge conductor 6. The transparent gauge 17, to show the height of the liquid in the tank, is supported by the fitting arms 17^a and 17^b which are screwed into the passages 2^a and 3^a, communicating with the tank at its upper and lower ends respectively. A mixing chamber or tube 18 is suspended and secured to the upper head 2 and is provided with an opening 18^a at its lower end to emit the gases and liquids to be mixed. A plurality of perforated spherical discs, oppositely superimposed over each other within said mixing chamber are provided to further and finally mix said liquid and gas when same is drawn off for use. Said mixing chamber is connected at its upper end with the conductor or tube 20 which is connected at its other end to the coil 21. Said coil is positioned around the outside of tank member 1 and is connected at its other end to the distributing chamber 22. Said chamber is secured in position against the tank member 1 by the strap 23 which extends around said tank member, and is secured to said chamber by bolts 23^a. Valves 24 for drawing off the carbonated liquid are secured, preferably screwed into the distributing chamber 22. Though I have shown but two valves for drawing off the liquid, the capacity of my carbonator is not limited to this number. A second tank 25 preferably made of thin sheet metal so placed as to inclose the above mentioned tank is secured by its lower flange 25^a between the flanges of the tank member 1 and the lower head 3, thus forming a circumferential ice compartment 25^b for cooling said carbonated liquid. The carbonator is supported by the base 26 not necessarily secured thereto. A casing 27 is positioned on said base by a groove 26^a extending around therein adapted to receive the lower end of said casing. A suitable insulating material 28 is provided to fill the space between the outer face of the tank 25 and the inner face of the casing 27. Said tank 25 and said casing 27 are reinforced and secured together at their upper extremities by a channel or other suitable means 25^c. A cover 29 is provided to cover the tank 25 and casing 27, therefore enclosing the whole carbonator at the top.

It is obvious that with the handle of the

valve 11 in the position shown by solid lines that any liquid above the overflow pipe 7 or any gas, under pressure greater than atmospheric, will be discharged. It is also obvious that when the pressure within the tank is relieved the liquid from the supply main 8 is allowed to pass through the check valve into the tank reaching a height, level with the top of the overflow pipe.

It is further obvious that with the valve handle in the position shown by dotted lines that the overflow is closed and the line to the gas supply is opened allowing gas under pressure to enter the tank through the nozzle 6. The gas pressure should not be less than the water supply pressure and it should be, preferably, slightly in excess of the water supply pressure.

It is further obvious that with the valve handle in any intermediate position, as is generally the case when the carbonated liquid is continuously drawn from the valves 24, that the water or liquid and the gas from the supply lines are both permitted to enter the tank and in proportion to the open position of the valve handle.

Though I have shown and described a particular construction, combination and arrangement of parts and portions I do not wish to be limited to this particular construction, combination and arrangement but my invention resides in the construction, combination and arrangement substantially as set forth in the appended claim.

Having thus described my invention what I claim as new and desire to secure by Letters Patent is:

In an apparatus of the character described, a tank, a tube suspended in said tank with its entrance located near the bottom of the tank, and its exit delivering through the top of said tank, a duct for delivering water into said tank, a check valve in said duct adapted to open when the pressure of the water supply exceeds the pressure within the tank, a duct delivering gas into said tank, said gas delivery duct and said venting means including a common valve device located wholly outside of said tank for simultaneously controlling the venting means and the delivery of gas through the gas delivery duct.

In testimony whereof, I have hereunto set my hand at Los Angeles, California, this 6th day of January, 1922.

ELI E. SAGER.
